CLAIM

The ornamental design for a portable game device, as shown and described.

DESCRIPTION

FIG. 1 is a front, top and right side perspective view of my new design for a portable game device;

FIG. 2 is a front elevational view of the portable game device of FIG. 1;

FIG. 3 is a rear elevational view of the portable game device of FIG. 1;

FIG. 4 is a top plan view of the portable game device of FIG. 1;

FIG. 5 is a bottom plan view of the portable game device of FIG. 1;

FIG. 6 is a right side elevational view of the portable game device of FIG. 1; and,

FIG. 7 is a left side elevational view of the portable game device of FIG. 1.

The broken lines are for illustrative purpose only and form no part of the claimed design.
